HAIR WAVER

Lucynda I. Fink, Liscomb, Iowa

Application February 15, 1952, Serial No. 271,682

4 Claims. (Cl. 132—38)

1

This invention has to do with hair wavers.

An object of the present invention is to provide a hair waver which is adapted for permanent and temporary waving.

Another object of the present invention is to provide a hair waver which is readily assembled and disassembled and which produces waves simulating the naturally occurring waves.

A further object of the present invention is to provide a hair waver which lends itself to placement in the air with ease and facility.

Other objects and advantages of the invention will become apparent from the following description taken in conjunction with the accompanying drawing wherein:

Figure 1 is a top plan view of the hair waver of the present invention with the tines on both sides.

Figure 2 is an elevational view of the hair waver shown in Figure 1 taken from the near side thereof.

Figure 3 is a bottom view of the hair waver shown in Figure 1.

Figure 4 is an end elevational view of the hair waver shown in Figure 1 taken from the left end thereof.

Figure 5 is a sectional elevational view taken on the line 5—5 of Figure 4.

Figure 6 is a top plan view of only the holder of the hair waver of Figure 1.

Figure 7 is a top plan view of another form of the holder of the hair waver of the present invention with a tine on only the right side.

Figure 8 is a top plan view of still another form of the holder of the hair waver of the present invention with a tine on only the left side.

Figure 9 is a top plan view of another form of the hair waver of the present invention showing a different hand actuatable means.

Figure 10 is a fragmentary elevational view of the hand actuatable means of the hair waver of Figure 9.

Referring to Figures 1 to 6 of the drawing, the hair waver of the present invention comprises a holder 1 and a hair waving element 2 which is slidably and detachably supported upon the holder.

The holder 1, Figure 6, embodies an upstanding support or rod 3 having a pair of longitudinally curved tines 4 and 5 arranged adjacent the lower end thereof and connected to the support 3, the tines being adapted to embrace the hair of the head. As shown in Figures 1 and 6, the facing sides of the tines 4 and 5 each slope downwardly from the top to the bottom, while each of the facing sides is straight. A pair of bars 6 and 7 arranged in side by side spaced relation

2

are positioned longitudinally of and above and spaced from the tines 4 and 5 and have one end connected to the upper end of the support 3. A means or abutment 8 is on each of the bars 6 and 7 adjacent the other ends for a purpose to be subsequently explained.

The hair waving element 2 comprises a longitudinally curved finger 9 adapted to embrace the head, the finger being convexly curved and the finger, Figures 2, 3 and 5, having a series of spaced, vertical, transversely disposed curved rows of teeth 10 projecting from its under face, the rows of teeth being adapted to penetrate the strands of hair. On the upper surface of the finger 9 intermediate its ends is an upstanding lug, Figures 2 and 5, the lug being provided with a slideway 12 adjacent the upper end thereof.

As clearly shown in Figures 1, 2 and 4, the convexly longitudinally curved finger 9 of the hair waving element 2 is arranged with its teeth 10 facing downwardly in side by side spaced relation with respect to the tines 4 and 5 of the holder 1 and beneath and spaced from the bars 6 and 7, the slideway 12 of the upstanding lug 11 slidably receiving the bars 6 and 7. It is to be noted that the end of the finger 9 adjacent the support 3 is convex while the opposite end is concave. A hand actuatable means or thumb piece 13 is on the upper end of the lug 11, such means or piece being for positioning the finger 9 upon the hair of the head and enabling the movement of the bars 6 and 7 along the slideway 12 until the lug 11 is in engagement with the upper end of the support 3. With the lug 11 in its position of engagement with the upper end of the support 3 or the position of Figure 1, the abutments 8 on the bars 6 and 7 are in engagement with the adjacent portions of the slideway 12 and serve to hold the finger 9 in position with respect to the tines 4 and 5.

The form of the holder of Figure 7 is the same in specific structure as the form depicted in Figure 6, and above described in detail, except that the support 3 is provided with only a single longitudinally curved tine 15 which is on the right side of the bars 6 and 7.

The form of the holder of Figure 8 is the same in specific structure as the form depicted in Figure 6, except that the support 3 is provided with a single longitudinally curved tine 16 which is on the left side of the bars 6 and 7.

In the form of Figures 9 and 10, the hand actuatable means on the lug 11 is in the form of an arcuate wing 17.

In operation, the operator places the finger 9 upon the head so that it is transversely of the hair and then moves the finger to the right or left

about one-half an inch in the direction in which the rows of teeth 10 are curved. While holding the finger in such position, the holder 1 is brought into position so that the tines 4 and 5 are in longitudinal spaced alignment with respect to the finger, whereupon the tines are inserted under the hair and simultaneously the bars 6 and 7 are inserted in the slideway 12 of the lug 11 and the bars 6 and 7 caused to be moved along the slideway 12 until the lug 11 bears against the support 3 and the abutments 8 on the bars 6 and 7 bear against the adjacent portions of the slideway and thereby hold the finger in position with respect to the tines. This movement of the holder relative to the finger 9 effects the waving of the portion of the hair held therebetween. Next, the operator places another finger 9 upon the head alongside of the positioned holder 1 with the concave end of the finger opposite the concave end of the finger 9 in the positioned holder 1 and then moves such finger in the opposite direction for a like distance of about one-half an inch. While holding such another finger 9, another holder 1 is brought into position so that the tines 4 and 5 face in the opposite direction from the tines 4 and 5 of the positioned holder, thereupon the tines are inserted under the hair and the flat side of the tine 5 caused to abut against the flat side of the tine 5 of the positioned holder 1 and simultaneously the bars 6 and 7 of the other holder are inserted in the slideway 12 of the lug 11 and the bars 6 and 7 caused to be moved along such slideway until the lug 11 bears against the support 3 and the abutments 8 on the bars 6 and 7 bear against the adjacent portions of the slideway and thereby hold the finger in position with respect to the tines. This movement of the other holder relative to the corresponding finger 9 also effects waving of the portion of the hair held therebetween with the crest of the wave being formed by the abutting tines 5 of the two positioned holders. At this point, the first positioned holder 1 is withdrawn while securely holding the finger, and then the finger is raised from the hair. The thus described operation is repeated with adjacent portions of the hair. In place of the holder having the two tines, the form of Figure 6, being employed, the holders of Figures 7 and 8 may be successively employed while the finger is in position upon the hair of the head.

Having fully described the invention what I claim is new and desire to secure by Letters Patent is:

1. A hair waver comprising an upstanding support, a longitudinally curved tine arranged adjacent the lower end of said support and connected to said support adapted to embrace a head, a pair of bars arranged in side by side spaced relation positioned longitudinally of and above and spaced from said tine and having one end connected to the upper end of said support, a longitudinally curved finger arranged in side by side spaced relation with respect to said tine and beneath and spaced from said pair of bars, said finger having a series of spaced vertical transversely curved rows of teeth projecting from its under surface adapted to penetrate strands of hair, an upstanding lug on the upper surface of said finger intermediate the ends of the latter, a slideway on said lug adjacent the upper end of the latter and slidably receiving said bars, and hand actuatable means on the upper end of said lug for positioning said finger upon the hair of the head.

2. A hair waver comprising an upstanding support, a longitudinal curved tine arranged adjacent the lower end of said support and connected to said support adapted to embrace the head, a pair of bars arranged in side by side spaced relation positioned longitudinally of and above and spaced from said tine and having one end connected to the upper end of said support, a longitudinally curved finger arranged in side by side spaced relation with respect to said tine and beneath and spaced from said pair of bars, said finger having a series of spaced vertical transversely curved rows of teeth projecting from its under surface adapted to penetrate strands of hair, and a lug on the upper surface of said finger intermediate the ends of the latter, a slideway on said lug adjacent the upper end of the latter and slidably receiving said bars, hand actuatable means on the upper end of said lug for positioning said finger upon the hair of the head, and means on said bars adjacent the other ends and engageable with the adjacent portions of said slideway when said lug has been moved to its position of engagement with the upper end of said support for holding said finger in position with respect to said tine.

3. A hair waver comprising an upstanding support, a pair of longitudinally curved tines arranged in spaced relation adjacent the lower end of said support and connected to said support adapted to embrace the head, a pair of bars arranged in side by side spaced relation positioned longitudinally of and above and spaced from said tines and having one end connected to the upper end of said support, a longitudinally curved finger arranged in side by side spaced relation with respect to said tines and beneath and spaced from said pair of bars, said finger having a series of spaced vertical transversely curved rows of teeth projecting from its under surface adapted to penetrate strands of hair, an upstanding lug on the upper surface of said finger intermediate the ends of the latter, a slideway on said lug adjacent the upper end of the latter and slidably receiving said bars, and hand actuatable means on the upper end of said lug for positioning said finger upon the hair of the head.

4. A hair waver comprising an upstanding support, a pair of longitudinally curved tines arranged in spaced relation adjacent the lower end of said support and connected to said support adapted to embrace a head, a pair of bars arranged in side by side spaced relation positioned longitudinally of and above and spaced from said tines and having one end connected to the upper end of said support, a longitudinally curved finger arranged in side by side spaced relation with respect to said tines and beneath and spaced from said pair of bars, said finger having a series of spaced vertical transversely curved rows of teeth projecting from its under surface adapted to penetrate strands of hair, an upstanding lug on the upper surface of said finger intermediate the ends of the latter, a slideway on said lug adjacent the upper end of the latter and slidably receiving said bars, hand actuatable means on the upper end of said lug for positioning said finger upon the hair of the head, and means on said bars adjacent the other end and engageable with the adjacent portions of said slideway when said lug has been moved to its position of engagement with the upper end of said support for holding said finger in position with respect to said tines.
